UNITED STATES PATENT OFFICE.

ALDUS ARTHUR HOOPMAN, OF SEATTLE, WASHINGTON.

TOPICAL MEDICINE.

No Drawing.

Application filed July 6, 1925. Serial No. 41,883.

This invention relates to improvements in medicines for topical applications, having for an object to provide a solution useful for the treatment of surface or skin disorders, 5 wounds and bodily pains, the same being of such content as to produce upon application to affected parts, an effectual anodyne and antiseptic action, causing an anæsthetic effect for a period of time as well as sterilizing the treated part.

The medicine is compounded from the following components, in about the proportions stated:—

	Parts.
Iodine	20
Phenol	20
Menthol	20
Glycerine	20
Grain alcohol	20

20 In compounding or producing the improved medicine, I preferably mix 20 parts of alcohol with 20 parts of glycerine at ordinary room temperature, add 20 parts of melted phenol, then add 20 parts of resublimed iodine, whereupon the mixture is permitted to stand at room temperature for approximately 48 hours or until the same takes on a clear reddish brown color. Then

20 parts of menthol are added to the mixture and the whole is then permitted to stand at normal temperature for a second period of time of approximately 24 hours, whereupon the solution is ready for packaging in bottles or other receptacles of suitable design for usage. The glycerine and 35 alcohol form the solvent vehicle in which the other ingredients (or their reaction products) are carried.

The medicine when applied topically is efficient for the relief of bodily pains, such 40 as neuralgia, pruritis, headache, rheumatism, also treatment of skin or surface disorders such as bites of insects, abscesses, ulcers, poisoning and glandular enlargements; furthermore, the medicine may be 45 used in treating cuts, abrasions, and other open wounds to prevent infection and allay pain.

I claim:—

A topical medicine comprising substantially equal parts of resublimed iodine, 50 phenol and menthol, in solution in a solvent vehicle consisting of glycerine and alcohol.

In witness whereof I have hereunto set my hand.

ALDUS ARTHUR HOOPMAN.
